UNITED STATES PATENT OFFICE.

HENRY G. ROTH, OF MINNEAPOLIS, MINNESOTA.

DESIGN FOR A DISPLAY-FIXTURE FOR STORES.

SPECIFICATION forming part of Design No. 34,404, dated April 23, 1901.

Application filed January 24, 1901. Serial No. 44,638. Term of patent 14 years.

To all whom it may concern:

Be it known that I, HENRY G. ROTH, a citizen of the United States, residing at Minneapolis, Hennepin county, Minnesota, have invented and produced a new and original Design for a Display-Fixture for Stores, of which the following is a specification, reference being had to the accompanying drawing, forming part thereof.

In the drawing the single view is a perspective illustrating a display-fixture embodying my new design.

As herein shown, the leading and material feature of the design is the border formed by the intersecting circles a and a' , the former of which bow upward and the latter of which bow downward. The circles a form a series

of depending points a^2 at their junction, and between the semicircles a and a' a series of double-convex surfaces a^3 are formed. An outwardly-curved surface b extends upward and outward from the border formed as above described.

What I claim, and desire to secure by Letters Patent of the United States, is as follows:

The design for a display-fixture for stores, substantially as herein shown and described.

In testimony whereof I affix my signature in the presence of two witnesses.

HENRY G. ROTH.

Witnesses:

MABEL M. MCGRORY,
FRANK D. MERCHANT.
